ROTATABLE DISK PICTURE TOY

Alexander Rosenfeld, Hollywood, Calif.

Application August 8, 1958, Serial No. 52,123

Term of patent 3½ years

(Cl. D34—15)

Figure 1 is a front perspective view of a rotatable disk picture toy showing my new design.

Figure 2 is a vertical sectional view taken on line 2—2 of Figure 1.

Figure 3 is a rear elevational view of Figure 1.

I claim:

The ornamental design for a rotatable disk picture toy, as shown.
